UNITED STATES PATENT OFFICE.

JOSEPH COLDWELL AND CHRISTOPHER GILES GILDARD, OF FALL RIVER,
MASSACHUSETTS.

DESIGN FOR A DROP-BAR.

SPECIFICATION forming part of Design No. 31,002, dated June 13, 1899.

Application filed March 31, 1899. Serial No. 711,291. Term of patent 14 years.

To all whom it may concern:

Be it known that we, JOSEPH COLDWELL and CHRISTOPHER GILES GILDARD, citizens of the United States, residing at Fall River, in the county of Bristol and State of Massachusetts, have invented and produced a new and original Design for Drop-Bars, of which the following is a specification, reference being had to the accompanying drawings, forming part thereof, in which—

Figure 1 is an elevation, and Fig. 2 a longitudinal central sectional view, of a drop-bar for electrically-operated stop-motions for looms, showing our new design.

As shown in the drawings, the leading or material feature of our design consists in a drop-bar of bifurcated form, comprising the

opposite terminals 1 1, the inner edges of which produce the intermediate slot 2, that extends from the lower ends of the terminals to a point near the upper end of the bar, finally merging into an eye 3, which is circular, the lower ends of the terminals being slightly reduced, so as to form points 5.

Having described our invention, what we claim as new is—

The design for a drop-bar, as herein shown and described.

JOSEPH COLDWELL.
CHRISTOPHER GILES GILDARD.
